ROLLER LEVELER

Richard W. Moses, Pittsburgh, Pa., assignor to
United Engineering & Foundry Company, Pitts-
burgh, Pa., a corporation of Pennsylvania

Application June 20, 1932, Serial No. 618,113

8 Claims. (Cl. 153—54)

My invention pertains to roller levelers, that is to say, to apparatus in which plates are straightened by subjecting them to the action of two opposed sets of rollers, the rollers of the two sets being so disposed that the plate is forced into a wave shape in passing between them, successive portions of the plate being bent in one and then in the other direction.

To effect the straightening of the plate, it is requisite that the metal thereof be flexed, by the action of the rollers, beyond its elastic limit, so as actually to be bent first one way and then the other. Since the plates will vary in thickness as well as in the character of their constituent metal, the amount of flexing necessary to obtain the required bending effect will likewise vary. Provision can be made, to an extent, for this variation by making the opposed sets of rollers adjustable as to the distance which separates them, and this is the common practice, especially with roller levelers having a relatively large number of rollers. The variation in the character of the plates could be accommodated better by adjusting, instead of, or in addition to, the adjustment of the distance between the opposed sets of rollers, the distances separating the individual rollers of each set. But this, with roller levelers employing a relatively large number of rollers as heretofore constructed, would be so tedious and difficult a job as hardly to be practicable.

It is the principal object of my invention to provide a roller leveler of a simple and economical construction and employing a relatively large number of rollers, in which the individual rollers of the two opposed sets can be adjusted, as regards the distances separating them, easily, quickly and with entire accuracy.

A roller leveler constructed in accordance with my invention is described by way of example in the following specification and shown in the accompanying drawings. I wish it understood however that the invention may be embodied in other constructional forms, and that changes may be made in the form which has been selected for description and illustration, without exceeding the scope thereof as defined in the appended claims.

In the drawings:

Fig. 1 is a diagram illustrating the action of a roller leveler of this type in straightening a plate;

Fig. 2 is an elevation, partly in section, of a roller leveler constructed in accordance with my invention, the section being taken on the line 55 II—II of Fig. 3; and

Fig. 3 is an end elevation partly in section taken on the line III—III of Fig. 2.

Referring to Fig. 1, a roller leveler of this type comprises an upper set of rollers 10 and a lower set of rollers 11, the rollers of each set being usually, but not necessarily spaced equidistantly apart, and the rollers of one set being centrally of the spaces between the rollers of the other set. In the figure in question only a few of these rollers are shown, but in practice a relatively large number will generally be employed. The rollers are positively driven in any well known manner that will admit of their adjusting movements,—such as by universal driving shafts or the like. The two sets of rollers are placed at such a distance apart that a plate, designated A, passed between them, will be bent, in successive portions, first upwardly and then downwardly, in the manner shown. It will be apparent that the amount of flexing of the plate to obtain a given bending effect, can be varied by adjusting the distance, b, between the two sets of rollers. The desired degree of flexing can, however, be obtained better by adjusting instead, or in addition, the distance c which separates the individual rollers of each set. My invention is primarily concerned with the provision of a means for obtaining the last-named adjustment readily.

Referring now to Figs. 2 and 3, the roller leveler therein shown comprises a pair of longitudinal base members 12, each formed with rails 12a upon which are slidably mounted bearing blocks 13 for the necks, 11a, of six rollers 11 spaced equidistantly apart. Disposed above the base members 11 are a pair of longitudinal supports 14, each formed with guideways 15 for slidably supporting the bearings 16 for the necks 10a of seven rollers 10, these rollers being separated by a distance equal to that which separates the rollers 11 of the lower set. The supports 14 are mounted at their ends for vertical movement upon standards 17 which are threaded into the base members 12, the supports being sustained by helical springs 18 disposed between them and the base members. By screwing the standards 17 into or out of the base members the distance between the two sets of rollers can be adjusted, and the adjustment, if desired, can be made so that the two sets of rollers are closer together at the end at which plates enter than at the other end, whereby the flexing is made to decrease as the plate passes through the leveler.

Shafts 19 are mounted in suitable bearings, 110

- 20, in the guideways of the support members 14, and have threaded portions 19b, 19c and 19d engaging in nuts 21 which are carried by all of the bearings 16, except the bearings for the center roller. The bearings for the center roller, which always occupies the same position, are merely provided with sleeves, 22, in which the center portions 19a of the shafts 19 can rotate freely. The pitch of the threaded portions of the shafts 19 is progressively greater from the center outwards, being such that when the shaft 19 is rotated the rollers 10 on each side of the center roller will be moved, towards or from the center roller, a given distance, the next pair of rollers twice that distance, and the outermost pair of rollers three times that distance. To that end, the pitch of the threaded portions 19c is twice, and of the threaded portions 19d three times, that of the threaded portions 19b. In these circumstances, rotation of the shaft 19 will either spread or bring together the rollers 10, while maintaining the equidistant relation between such rollers. The rotation of the shafts is effected by means of a transverse shaft 23 having worm and wheel connection with the shafts 19, and adapted to be operated by a hand-wheel 24.

In the rails 12a of the base members 12 are rotatably mounted shafts 25 having threaded portions 25b, 25c and 25d which engage nuts 26 carried by the bearings 13. The construction is similar to that employed for the upper rollers, except that there is no stationary center roller. The shafts 25 are rotated by means of a transverse shaft 27, similar to the shaft 23 and operated by means of a hand-wheel 28. The pitch of the threaded portions 25c is three times, and of the threaded portions 25d five times, that of the middle threaded portions 25b. Under these conditions, the rotation of the shafts 25 to a proper extent will keep the rollers of the lower set spaced centrally between the rollers of the upper set.

The shafts 23 and 27 may be independent, in which case it is desirable to provide index means by means of which the operator can read the extent to which he has moved the rollers, and thereby be able to maintain, during the adjustment, the proper position of the rollers of one set with respect to the rollers of the other set. Or, the shafts 23 and 27 may be connected by a chain 29 passing over sprockets on the shafts. If, as shown, the gear relation between the shafts 23 and 27 is one to two, the pitch of the middle threaded portions 19b of the shafts 19 and of the middle threaded portions 25a of the shafts 25 would be the same. With the shafts geared for equal rotation, the pitch of the middle threaded portions 25a of the shafts 25 would be one-half that of the middle threaded portions 19b of the shaft 19.

When the leveler is to be adjusted for a new character of plate to be straightened, all that is necessary is for the operator to manipulate the shafts 23 and 27,—or, if these shafts are geared together, to manipulate one of them,—in such manner as to spread the rollers or bring them together in such a way as to produce the best results in straightening the particular character of plate being handled. An adjustment, also, of the distance between the sets of rollers can be made by means of the threaded standards 17, if desired. The result is that the leveler, by means of adjustments which are easily, quickly and accurately performed, can be made to operate

at its highest degree of efficiency upon plates of widely varying characters.

While I have shown and described, by way of example, a roller leveler in which the rollers are equidistant from each other, it will be appreciated that my invention is adapted for use in connection with levelers in which the rollers are otherwise spaced since any desired spacing may be secured or maintained by suitably relating the pitches of the several screw threads.

I claim:

1. A roller leveler comprising a series of rollers arranged in train, a second series of rollers arranged in train and disposed opposite the first series in staggered relation therewith, said rollers being arranged to successively engage sheet metal passing between the first and the second series thereof, and means for simultaneously moving the rollers of both of said series in the direction of the trains to vary the distances between the axes of the rollers of the leveler, whereby said distances can be adjusted during the operation of the leveler.

2. A roller leveler including two opposed series of rollers, one of said series comprising a roller, a second roller disposed in train therewith, and means for moving said first-named roller transverse to its axis in the line of the train and with respect to a given point and simultaneously moving said second-named roller transverse to its axis in the line of the train, said means being constituted so that during movement of said first and second-named rollers the distance therebetween is maintained equal to the distance between said first-named roller and said point.

3. A roller leveler including two opposed series of rollers, the rollers of each series being arranged in train and equidistantly between the rollers of the opposite series, a mechanism for simultaneously moving the rollers of one series transversely of their axes through distances having the ratio 1, 2, 3, and a mechanism for simultaneously moving the rollers of the other series transversely of their axes through distances having the ratio 1, 3, 5.

4. A roller leveler including two opposed series of rollers, the rollers of each series being arranged for successively engaging sheet metal passing between said series, one of said series comprising a roller, a mounting therefor, a second roller disposed in train with said first-named roller, a mounting for said second-named roller, and means for moving said first-named roller transverse to its axis in the line of the train and with respect to a given point and simultaneously moving said second-named roller transverse to its axis in the line of the train, said means including two members each having a screw-thread connection with one of said mountings, the pitch of the screw threads of one member being such with respect to those of the other member that during movement of said first and second-named rollers the distance therebetween is maintained equal to the distance between said first-named roller and said point.

5. A roller leveler comprising two opposed series of rollers, the rollers of each series being arranged in train for successive engagement by sheet metal passing through the leveler, and equidistantly between the rollers of the opposite series, mountings for the rollers of one series, means for moving the rollers of said series transversely of their axes and comprising members threaded into said mountings and having the pitch of the threads thereof in the ratio of 1, 2, 3, mountings for the

1

rollers of the other series, and means for moving the second-named series of rollers, said means comprising members threaded into said mountings and having the pitch of the threads thereof 5 in the ratio of 1, 3, 5.

6. A roller leveler comprising a series of rollers arranged in train, a second series of rollers arranged in train and disposed opposite the first series in staggered relation thereto, said rollers 10 being adapted to successively engage sheet metal passing between the first and second series thereof, and means operable during the operation of said leveler for simultaneously moving rollers of each of said series in the direction of the train 15 through distances of progressively varying lengths to vary the distances between the axes of the rollers of said series.

7. A roller leveler comprising a series of rollers arranged in train, a second series of rollers arranged in train and disposed opposite the first 20 series in staggered relation thereto, said rollers

being adapted to successively engage sheet metal passing between the first and second series thereof, and means operable during the operation of said leveler for simultaneously moving rollers of each of said series in the direction of the train through distances of progressively varying lengths to vary the distances between the axes of the rollers of said series.

8. A roller leveler comprising a series of rollers arranged in train, a second series of rollers arranged in train and disposed opposite the first series in staggered relation thereto, said rollers being adapted to successively engage sheet metal passing between the first and second series thereof, and means operable during the operation of said leveler for simultaneously moving rollers of both of said series in the direction of the train through distances of progressively varying lengths to vary the distances between the axis of the rollers of the leveler.
